(57) **CLAIM**

The ornamental design for an antenna for digital terrestrial broadcasting receiving, as shown and described.

DESCRIPTION

FIG. 1 is a front perspective view of an antenna for digital terrestrial broadcasting receiving showing our new design;

FIG. 2 is a front elevational view thereof;

FIG. 3 is a right side elevational view thereof, the left side elevational view being a mirror image;

FIG. 4 is a rear elevational view thereof;

FIG. 5 is a top plan view thereof;

FIG. 6 is a bottom plan view thereof; and,

FIG. 7 is a partial cross sectional view of the bottom section of the antenna.
